UNITED STATES PATENT OFFICE.

GUSTAV E. FRITZ, OF PEORIA, ILLINOIS.

ARTIFICIAL TOOTH.

1,136,664.

Specification of Letters Patent. Patented Apr. 20, 1915.

Application filed June 15, 1912. Serial No. 703,849.

To all whom it may concern:

Be it known that I, GUSTAV E. FRITZ, a citizen of the United States, residing at Peoria, in the county of Peoria and State 5 of Illinois, have invented certain new and useful Improvements in Artificial Teeth, of which the following is a specification.

This invention has reference to certain new and useful improvements in artificial 10 teeth.

My invention is clearly illustrated in the accompanying drawings, which, with the characters of reference marked thereon form a part of this specification, and in 15 which:—

Figure 1 is an enlarged sectional view of a bicuspid embodying my invention; the backing and pin shown in dotted lines applied to the tooth; Fig. 2 is a view of the 20 bicuspid seen in Fig. 1 looking at one of its approximal faces, the backing and pin removed; Fig. 3 is a cross-section in plan as the same would appear if taken on the line 3—3 of Fig. 2 and with the backing 25 applied to the tooth; Fig. 4 is a cross-section as the same would appear if taken on the line a—a of Fig. 1; Fig. 5 is a cross-section as the same would appear if taken on the line b—b of Fig. 1; Fig. 6 is a perspective view of the backing and pin for a bicuspid, such as shown in Fig. 2; Fig. 7 is a 30 perspective view of a boxing or lining such as would be used to line the walls of an opening, groove or cavity in the tooth shown 35 in Fig. 1.

The tooth 1 has the buccal surface 2, the lingual surface 3, the gingival margin 4, the buccal cusp 5 and the lingual cusp 6.

7 indicates what is known as the "rub- 40 ber-line-shoulder." The "rubber-line-shoulder" and the lingual surface 3 proper, are divided by a depression 8 which is formed by beveling or tapering the lingual surface 3 and 9 from the "rubber-line 45 shoulder" 7 downwardly and forwardly in the direction of the buccal surface and at a predetermined point such surface is beveled or tapered downwardly and rearwardly, as at 10, to the lingual surface proper. The 50 lingual surface 3, proper, from the point where the beveled surface 10 and the lingual surface proper merge into each other, which in reality is a shoulder, is beveled or inclined downwardly and forwardly in the direction 55 of the buccal surface 2 and at a predeter-

mined point, designated 11, the angle of the lingual surface 3 is changed extending approximately vertically but at a slight angle and said lingual surface continues and merges into the gingival margin 4; from 60 which, the buccal surface 2 extends outwardly and upwardly into the buccal cusp 5. The lingual surface 3, although beveled or inclined forwardly and downwardly, as shown in Fig. 1, presents a flat surface 65 transversely of the tooth, as shown in Fig. 3. The tooth also has an opening, groove or cavity 12, and said opening, groove or cavity 12 is lined with a metallic boxing or lining 13, preferably open at both ends. The opening, groove or cavity 12 is much larger in cross-section where the same opens out of the lingual surface 3, than at its inner end, and said opening, groove or cavity tapers gradually from the lingual surface to its 70 inner terminus. The groove, opening or cavity 12 is curved, its upper wall being preferably struck on a radius which is shorter than the radius on which the lower wall is struck. In this way the tapering 75 depth of the opening, groove or cavity from end to end is determined. The groove, opening or cavity 12 opens out of the lingual surface 3, as was stated, and terminates in the buccal cusp 5. I prefer that the groove, 80 opening or cavity 12, shall be wedge-shaped in cross-section, see a section of the pin in Figs. 4 and 5, and that the upper wall thereof shall be wider, or of greater width than its lower wall. With this construc- 85 tion and with the boxing or lining 13 in place, when the pin is applied, I have strength, where strength is needed. I also prefer that the lower wall of the lining or boxing 13 at the lingual surface 3 shall be 90 contiguous to the point 11 where the angle of the lingual surface 3 changes. In other words, the opening 12 into the tooth is in the inclined portion of the lingual surface 3. The boxing or lining 13, as will be understood, conforms to the walls of the opening 12.

The approximal surfaces 14 of the tooth 1 are beveled or formed with the depressions 15. The upper walls 16 of these depressions, which in reality are shoulders, lead from and merge into the depression 8 in the lingual surface 3 of the tooth and extend forwardly and downwardly at a slight incline 105 toward the buccal surface and at 17 said 110

walls or shoulders 16 turn and lead downwardly and rearwardly as at 18 toward the lingual surface, merging into the same at the point 11. The depressions 15 although 5 flat, see Fig. 3, are inclined or beveled, converging from the shoulders 17 and 18 toward the lingual surface, into which they merge, see also Fig. 3.

19 designates a pin, or backing securing member, which preferably conforms to and has the same contour and outline as the opening 12 and lining or boxing 13 in the tooth, and said pin has the enlarged and flared head 20.

21 designates a backing of metal or other suitable material. Said backing has the portion 22 adapted to rest against and conform to the lingual surface 3, with the lower beveled portion 23 adapted to lie against the 26 lingual surface 3 between the point 11 on the lingual surface, and the gingival margin 4. The upper part of the backing 21 has the portion 24 which inclines forwardly and upwardly, see Fig. 1, adapted to fit the inclined surface 10 of the depression 8 in the lingual surface and with the upper flat edge 25 of the backing abutting with the inclined surface 9 of the depression 8 in the lingual surface. When the backing is in place, see 30 the dotted lines Fig. 1, the lingual cusp and the face of the portion 24 of the backing, at the "rubber-line-shoulder" 7, are flush and form a continuation, one of the other.

The backing 21 has an opening 26 which is 35 large enough for the pin 19 to be passed therethrough, but sufficiently small to prevent the head 20 passing through. The walls of the opening 26 are flared to conform to and form a seat for the head 20 40 of the pin 29. The backing 21 is further provided with the side walls 27. Said walls are adapted to the depressions 15 in the proximal faces of the tooth. The edges 28 of the walls 27 fitting under and engaging 45 the shoulders 16 of the depressions, while the edges 29 engage and rest against the shoulders 18 of the depressions.

When the backing 21 and the pin 19 are 50 adapted to the tooth, the tooth, as it were, sits in a box. The peculiar formation or curving of the opening, groove or cavity in the tooth and the curved pin forms a locking connection between the tooth, pin and backing, which will prevent the tooth from 55 moving forward on the pin or the separation of the tooth at the lingual cusp from the backing, and the walls 27 of the backing seated in the depressions 15 of the tooth adds additional strength to the tooth and 60 also allows greater bulk of solder between

teeth, especially when several teeth are assembled.

The opening, groove or cavity 12 may be of any suitable shape, in cross-section, either round, square, wedge-shaped, dove-tailed or 65 triangular and the pin of course is of similar formation. The essential features being that the opening and pin are curved, leading in from the lingual surface and terminating in the buccal cusp. 70

While I have illustrated my improvements in connection with only a bicuspid, it is to be understood that the invention may be carried out and applied with equally as good results on the various teeth, especially is this 75 true of the curved groove, opening or cavity in the tooth which may be applied to porcelain bite teeth having a rubber line, as well as to the anterior facings.

What I claim is:—

1. A tooth formed with a buccal cusp and a "rubber-line-shoulder," and also having a sloping lingual surface, said surface adjacent the shoulder having a depression produced by oppositely inclined faces; said tooth also having a curved cavity opening out of the lingual surface and terminating in the buccal cusp; a curved pin and a backing, said backing having a portion to fit against the lingual surface proper and also 90 provided with a portion adapted to be seated in the depression in the lingual surface, when the pin is in the cavity of the tooth. 80

2. A tooth having a cavity which is curved longitudinally and wedge shaped in cross 95 section and opening out of the lingual surface thereof; a backing for the tooth having an opening; a pin for securing the tooth and backing together, said pin curved throughout its length and wedge shaped in 100 cross section and having a head adapted to be seated in the opening in the backing.

3. A tooth having a "rubber-line-shoulder" and a sloping lingual surface, said surface adjacent the "rubber-line-shoulder" 105 having a depression produced by oppositely inclined faces; the proximal wall of the tooth formed with depressions, one wall of the depressions merging into the deepest portion of the depression in the lingual surface and another wall of said depression merging into the lingual surface at a predetermined point between the gingival margin and said depression in the lingual surface. 110

In testimony whereof I affix my signature, 115 in presence of two witnesses.

GUSTAV E. FRITZ.
